[57] CLAIM

The ornamental design for a beverage glass or similar article, as shown and described.

DESCRIPTION

FIG. 1 is an elevational view of a beverage glass or similar article showing my new and ornamental design in the size and proportions of a goblet.

FIG. 2 is a top plan view thereof.

FIG. 3 is a bottom view thereof.

FIG. 4 is a central sectional view thereof taken along and in the direction of the sectional plane 4—4 designated in FIG. 1.

FIG. 5 is a sectional view thereof taken along and in the direction of the sectional plane 5—5 in FIG. 1.

FIG. 6 is a sectional view thereof taken along and in the direction of the sectional plane 6—6 in FIG. 1.

FIG. 7 is a sectional view taken along and in the direction of the sectional plane 7—7 in FIG. 1.

FIG. 8 is a sectional view taken along and in the direction of the sectional plane 8—8 in FIG. 1.

FIG. 9 is an elevational view of my new and ornamental design in the size and proportions of a wine glass.

FIG. 10 is an elevational view of my new and ornamental design in the size and proportions of a cocktail glass.

FIG. 11 is an elevational view of my new and ornamental design in the size and proportions of a "whiskey sour" style of cocktail glass.

FIG. 12 is an elevational view of my new and ornamental design in the size and proportions of a champagne glass.
